UNITED STATES PATENT OFFICE

MARGARET M. FONES, OF NEW YORK, N. Y.

MENDER ATTACHMENT FOR SEWING MACHINES

Application filed January 5, 1929. Serial No. 330,558.

This invention relates to an adjusting attachment for sewing machines, and, more particularly, to an attachment by which the presser-foot may be adjusted and held by the resilient friction of the said attachment at variable distances above the cloth to be sewed, and, especially in that branch of sewing known as "mending".

The object of the invention is to provide a simple and effective, easily operated device, adaptable to all types of sewing machines, by means of which the presser-foot may be readily raised or lowered, as occasion requires, and frictionally held at will at the exact distance above the piece or pieces of cloth or other fabric to be sewed, which will best accommodate the thickness of the materials to be sewed.

The advantages of my invention are:—The mender will hold the presser-bar and presser-foot absolutely stationary whenever desired at any distance from the feed-teeth by lifting or lowering the bar with one or two fingers, thus making it possible, while using any kind of power or speed, to mend goods freely in any direction without causing resistance, friction, or breakage of thread. It does not interfere with the tension or any working part of the machine,—is small, and does not obstruct,—is conveniently placed, and the mending done with it never thickens on either side of the goods. The work can be removed and again inserted all day if necessary without touching the mender, or it can be changed instantly to straight-away work without the slightest inconvenience. It can mend the thickest comfortable, quilt, or blanket, or the thickest or thinnest clothing. It saves time noticeably, also money, requires no extra assistance from legs or feet, and tends to improve and preserve the health of the operator, and greatly lessen the burden of mending garments and heavy cloths.

In its preferred form my invention consists primarily of a resilient friction member adapted to be attached to some desired part of the needle post of the sewing machine, adjacent to the bar of the presser-foot,—a cam-lever for raising and lowering the bar and connecting means between the

lever and the friction member by which a sliding connection is always maintained between said member and said cam-lever, of a slightly resilient character, and with sufficient pressure to maintain said cam-lever at 55 the desired point against the force of gravity, wherever the adjusting motion is stopped.

In the accompanying drawings is shown the simplest form in which I have, as yet, embodied my invention, but it is to be understood that many changes in details of structure may be made without departing from the spirit of my invention.

Figure 1 is a front elevation.

Figure 2 is a side elevation.

Figure 3 is an associative view of the various details, aligned in the order of their association.

Same letters indicate similar parts in the different figures.

A is the cam-lever, having the usual pivot hole *a*, by which it hangs on a suitable pin inside the casing which covers the usual needle-bar, and presser-bar, shown in Figures 1 and 2. The operation of this cam-lever upon the presser-bar, in raising and lowering it is of the well-known and usual character. No change in this or other parts of the sewing machine is needed to accommodate my new attachment.

B is a thumb-screw, and C, a slotted bracket to be attached to the casing, as by screws, in such a manner that the cam-lever has free play to co-operate with the slot *c*, curved as shown, approximately to form an arc of a circle, the centre of which is the pin inside the needle post, upon which the head of the cam-lever is hung, in order to accommodate the normal shifting of the cam-lever up and down.

The association of the three most important parts of this simplest form of my new mender attachment,—namely, the cam-lever, the adjusting thumb-screw, and the slotted holding plate, may be accomplished by passing the stem of thumb-screw B, through a hole *b*, made in the shank of the cam-lever,—through washer *d*, slot *c*, split washer *e*, and tightened by nut *f*, as shown in Figure 3.

The tension between the side of the cam-

lever and the surface of the slotted plate merely determines the resilient resistance which has to be overcome to permit the lever to be shifted from one point of the slot to another, thus determining the height of the presser-foot above the material to be mended or sewed. This tension is, preferably, made slight,—in fact, just strong enough to overcome the downward thrust of the usual presser bar spring to which the cam-lever is always subject. This tension, in my preferred construction is obviously so slight that no screw is needed,—the natural resilience of the thin metals of which the bracket is made being enough, in itself, to create the tension desirable.

I claim:—

1. In a sewing machine, a head, a presser foot, a presser foot lifting lever, a member secured to the head adjacent the presser foot lifting lever, and means carried by said lever and having a yieldable, frictional, sliding engagement with said member, whereby said lever may be manipulated in the usual manner to raise and lower the presser foot and will be automatically maintained in any position in which it is put.

2. In a sewing machine, a head, a presser foot, a presser foot lifting lever, a member secured to the head adjacent the presser foot lifting lever, said member having an arcuate slot, and means carried by said lever and having a yieldable, frictional, sliding engagement within the slot of said member, whereby said lever may be manipulated in the usual manner to raise and lower the presser foot and will be automatically maintained in any position in which it is put.

MARGARET M. FONES.
